The ornamental design for a pattern for a sock, as shown and described.

DESCRIPTION

FIG. 1 is a bottom plan view of a first embodiment for a pattern for a sock, showing the new design;

FIG. 2 is a side elevation view thereof;

FIG. 3 is a front elevation view thereof;

FIG. 4 is a perspective view thereof;

FIG. 5 is an enlarged view of an area labeled "5" in FIG. 4;

FIG. 6 is a bottom plan view of a second embodiment for a pattern for a sock;

FIG. 7 is a side elevation view thereof;

FIG. 8 is a front elevation view thereof;

FIG. 9 is a perspective view thereof; and,

FIG. 10 is an enlarged view of an area labeled "10" in FIG. 9.

Color forms no part of the claimed design.

The broken lines in FIGS. 4, 5, 9 and 10 are used to annotate an area of enlargement and form no part of the claimed design.
